Attorney.

UNITED STATES PATENT OFFICE.

SILAS M. FORD, OF ST. PAUL, MINNESOTA.

LATH-BOARD.

1,266,574.

Specification of Letters Patent. Patented May 21, 1918.

Application filed August 21, 1916. Serial No. 116,146.

To all whom it may concern:

Be it known that I, SILAS M. FORD, a citizen of the United States, residing at St. Paul, in the county of Ramsey and State of Minnesota, have invented certain new and useful Improvements in Lath-Boards, of which the following is a specification.

One object of my invention is to provide in a lath board improved air spaces that will 10 be left unfilled with plaster when the lath board is put into service.

Another object of my invention is to provide means, for applying to lath boards manufactured without the additional air 15 spaces contemplated in this invention, that can readily be applied to such lath boards and add thereto the additional air spaces contemplated herein.

Another object of my invention is to provide 20 a style of lath board that can be used either as an insulating medium between walls or floors, or as the commercial type of lath-board.

Another object of my invention is to provide 25 a lath board that can be positioned in a cement block or tile, furnishing an insulating wall through the body of the block or tile.

Another object of my invention is to provide 30 means for stiffening the lath board to prevent distortion.

With these and incidental objects in view, the invention consists of certain novel features of construction and combination of 35 parts, the essential elements of which are hereinafter described with reference to the drawing which accompanies and forms a part of this specification.

In the drawing Figure 1 is an isometric 40 view of a portion of a lath board embodying my preferred construction.

Fig. 2 is a similar view of a modification of the same type of board. Fig. 3 is a similar view of a second modification.

Fig. 4 is an isometric view of a portion of a still further modified form of inserted 45 strip used in the lath board, and Figure 5 is an isometric view of a cement block or tile embodying my improved insulating board.

A sheet of fibrous water-proof paper 1, or other suitable material, is corrugated or 50 plaited into a dove-tailed formation, as shown in Fig. 1 and in the space behind each of the lath-like projections a strip of 55 similar material is inserted.

This strip 2 is of sufficient width that when positioned as shown in the drawing, it maintains a curved shape so as to provide just behind the lath-like face an air space 3.

In the modification shown in Fig. 2, the strips 2 have a corrugated center 4 to provide additional elasticity, and flat strips 5 either thread through these corrugations as at 6, or the corrugations are slotted as at 7, and the strips laid therein.

In order to stiffen the corrugated sheet 1 without the use of the flat strips 5, I bend a strip of the material as at 8, giving the arch 9 with the air space 10 between the arch and the lath-like faces, and continue each 70 end of the arch into the Z-shaped lips 15, which are preferably glued or cemented to the corrugated sheet at 12, or if desired are cemented along the entire surface of contact.

The cementing of this Z-shaped strip at 75 12 and also along the surface 13 prevents the angle 14 from readily increasing in size, and as it is impossible for the board to become distorted without these angles 14 being increased, the construction gives a stiffened 80 effect to the corrugated board.

In addition the lips 15 terminating the Z-shaped formation serve to space the lath faces from the wall, and hence provide an air space between the wall and the back 85 faces of the board, as well as the air spaces 10 between the front faces and the arch 9.

I may also employ a strip shaped as shown in Fig. 4 in place of the strips 2 illustrated in the other figures for obtaining the 90 same results.

By forming a cement block or tile around a sheet of insulating board, as shown in Fig. 5, I secure a substantial solid block of cementitious material with continuous air 95 spaces extending through the center plane of the block and also with a water-proof medium extending through the central plane of the block.

While I have described my invention and illustrated it in several particular designs, I do not wish it understood that I limit myself to these constructions, as the application of my invention may be varied in many ways within the scope of the following 105 claims:

Claims:

1. In a lath board, the combination of a sheet of material formed into dove-tailed corrugations having alternate faces on 110

either side thereof, and a strip of material positioned adjacent to the inner surface of each of said faces, and below the plane of the opposite surfaces of said lath board, 5 thereby forming air spaces between said strips and the inner faces of said corrugated sheet.

2. In a lath board, the combination with a sheet of insulating material, formed into 10 dove-tailed shaped corrugations of means associated with said dove-tailed shaped corrugations positioned below the opposite face of said lath board for maintaining air spaces throughout the entire body of said sheet.

15 3. In a lath board, the combination of a sheet of material formed into substantially dove-tailed shaped corrugations, a strip of fibrous water proof material positioned within the depressions formed by said corrugations, and having sufficient resiliency to maintain itself entirely within said depressions and below the outer surface of the finished lath board.

4. In a lath board for insulating cementitious blocks or sheets, the combination of 25 a sheet of material corrugated into a series of substantially dove-tailed shaped corrugations and having strips of material positioned in each of the corrugations thus 30 formed and positioned below the face of the completed lath board for maintaining air spaces throughout the block or sheet of cement.

entitious material in which said insulating board is used.

5. In a lath board the combination of a 35 sheet of material formed into dove-tailed shaped corrugations, and spacing strips positioned on and running longitudinally of the faces formed in said sheet to space said faces from the wall to which said insulating board is applied, said spacing strips each having a fold or V-shaped section, one of the arms of the V-shaped section being positioned within the depression of the corrugations and the other arm lying along the 40 exterior of the lath-like faces.

6. In a lath board the combination of a sheet of insulating material formed into dove-tailed shaped corrugations, and reinforcing strips having V-shaped portions positioned over the outer angles of said dove-tailed corrugations, one arm of each V-shaped portion being positioned on the face of the lath-like projection formed, and the other arm being positioned within the de- 45 pression between the lath-like faces.

7. In a lath board the combination of a sheet of material formed into substantially dove tailed corrugations, a strip of material positioned in the depressions formed by 50 said corrugations, said strip being formed into a U shaped section with the ends out turned and the curve of the bight inverted.

SILAS M. FORD.
